(57) CLAIM

We claim the ornamental design for a soap dish assembly, as shown and described.

DESCRIPTION

FIG. 1 is a left side elevation of a soap dish assembly showing our new design, which is a mirror image of a right side elevation.

FIG. 2 front view thereof.

FIG. 3 is a rear view thereof.

FIG. 4 is a top view thereof.

FIG. 5 is a bottom view thereof; and,

FIG. 6 perspective view thereof.
